DISPENSING CONTAINER OR SIMILAR ARTICLE

Harold J. Vanderhyde, North Merrick, N.Y., assignor to The Procter & Gamble Company, Cincinnati, Ohio, a corporation of Ohio

Filed May 6, 1963, Ser. No. 74,761

Term of patent 14 years

(Cl. D58—17)

Fig. 2

FIG. 1 is a top plan view of a dispensing container or similar article showing my new design.

FIG. 2 is an elevational view of the same.

The side not shown is the same as the side shown.

I claim:

The ornamental design for a dispensing container or similar article, as shown and described.
